(57) **CLAIM**

The ornamental design for a transport tray, as shown and described.

DESCRIPTION

FIG. 1 is a perspective view of the top of the transport tray; FIG. 2 is a top view thereof;

FIG. 3 is a left side view thereof;

FIG. 4 is a front view thereof;

FIG. 5 is a right side view thereof;

FIG. 6 is a back side view thereof;

FIG. 7 is a bottom view thereof; and,

FIG. 8 is an enlarged of detail 8 in of the top of transport tray shown in FIG. 1.

The dash-dash broken lines depict portions of the transport tray that form no part of the claimed design. The dash-dot broken lines depict enlargement boundary limits that form no part of the claimed design.

1 Claim, 6 Drawing Sheets
